[57] CLAIM

The ornamental design for an aircraft, substantially as
shown and described.

DESCRIPTION

FIG. 1 is a perspective view of said aircraft;
FIG. 2 is an elevational view of one side of said aircraft,
the elevational view of the other side being substantially
a mirror image thereof;
FIG. 3 is a top plan view of said aircraft;
FIG. 4 is a bottom plan view of said aircraft;
FIG. 5 is an elevational view of the front of said aircraft;
FIG. 6 is an elevational view of the rear of said aircraft.
